CLAIM

An ornamental design for a servo device, as shown and described.

DESCRIPTION

FIG. 1 is a front view of a servo device;

FIG. 2 is a rear view of FIG. 1;

FIG. 3 is a top view of FIG. 1;

FIG. 4 is a bottom view of FIG. 1;

FIG. 5 is a right side view of FIG. 1;

FIG. 6 is a left side view of FIG. 1; and,

FIG. 7 is a perspective view of FIG. 1.

The broken lines shown in the drawings illustrate portions of the servo device that for no part of the claimed design.

1 Claim, 7 Drawing Sheets
